ORNAMENTAL PANEL.

No. 19,477.

Patented Dec. 10, 1889

UNITED STATES PATENT OFFICE.

ALLAN B. CAMERON, OF WILLIAMSPORT, PENNSYLVANIA.

DESIGN FOR AN ORNAMENTAL PANEL.

SPECIFICATION forming part of Design No. 19,477, dated December 10, 1889.

Application filed November 12, 1889. Serial No. 330,082. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

My design relates to a rectangular panel having upon its surface the following ornamental configuration: A is a rectangular ele-

vation. From the center B of said elevation extend curved channels C to meet the edges of said elevation. The number of said channels is immaterial.
